(57) CLAIM

The ornamental design for a front facia for a motor vehicle, as shown and described.

DESCRIPTION

FIG. 1 is a front view of a front facia for a motor vehicle;

FIG. 2 is a top view thereof;

FIG. 3 is a bottom view thereof;

FIG. 4 is a right side view thereof;

FIG. 5 is a left side view thereof; and,

FIG. 6 is a perspective view thereof.

The rear surface of the front facia of a motor vehicle contains no ornamentality and is not part of the claimed design.

1 Claim, 6 Drawing Sheets
